(57) **CLAIM**

We claim the ornamental design for an ice skate blade holder, as shown and described.

DESCRIPTION

FIG. 1 is a lateral side perspective view of an ice skate blade holder according to a first embodiment of the present design; FIG. 2 is a medial side perspective view of the ice skate blade holder of FIG. 1;

FIG. 3 is a lateral side elevation view of the ice skate blade holder of FIG. 1;

FIG. 4 is a medial side elevation view of the ice skate blade holder of FIG. 1;

FIG. 5 is a top plan view of the ice skate blade holder of FIG. 1;

FIG. 6 is a bottom plan view of the ice skate blade holder of FIG. 1;

FIG. 7 is a front elevation view of the ice skate blade holder of FIG. 1;

FIG. 8 is a rear elevation view of the ice skate blade holder of FIG. 1;

FIG. 9 is a lateral side perspective view of an ice skate blade holder according to a second embodiment of the present design;

FIG. 10 is a medial side perspective view of the ice skate blade holder of FIG. 9;

FIG. 11 is a lateral side elevation view of the ice skate blade holder of FIG. 9;

FIG. 12 is a medial side elevation view of the ice skate blade holder of FIG. 9;

FIG. 13 is a top plan view of the ice skate blade holder of FIG. 9;

FIG. 14 is a bottom plan view of the ice skate blade holder of FIG. 9;

FIG. 15 is a front elevation view of the ice skate blade holder of FIG. 9;

FIG. 16 is a rear elevation view of the ice skate blade holder of FIG. 9;

FIG. 17 is a lateral side perspective view of an ice skate blade holder according to a third embodiment of the present design;

FIG. 18 is a medial side perspective view of the ice skate blade holder of FIG. 17;

FIG. 19 is a lateral side elevation view of the ice skate blade holder of FIG. 17;

FIG. 20 is a medial side elevation view of the ice skate blade holder of FIG. 17;

(Continued)

FIG. 21 is a top plan view of the ice skate blade holder of FIG. 17;
 FIG. 22 is a bottom plan view of the ice skate blade holder of FIG. 17;
 FIG. 23 is a front elevation view of the ice skate blade holder of FIG. 17; and,
 FIG. 24 is a rear elevation view of the ice skate blade holder of FIG. 17.
 The broken lines depict environment subject matter only and do no form part of the claimed design.
